Primary Examiner — Mark Goodwin(74) *Attorney, Agent, or Firm* — McAndrews, Held & Malloy, Ltd.(57) **CLAIM**

The ornamental design for multi-article packaging, as shown and described.

DESCRIPTION

FIG. 1 is a perspective view of the multi-article packaging showing articles positioned in the packaging in broken lines. The broken lines shown in any of the Figures are for the purpose of illustrating the environmental structure of the multi-article packaging and are not part of the claimed design. FIG. 2 is a front view of the multi-article packaging of FIG. 1. FIG. 3 is a back view of the multi-article packaging of FIG. 1. FIG. 4 is a left side view of the multi-article packaging of FIG. 1.

FIG. 5 is a right side view of the multi-article packaging of FIG. 1.

FIG. 6 is a top view of the multi-article packaging of FIG. 1. FIG. 7 is a bottom view of the multi-article packaging of FIG. 1.

FIG. 8 is a perspective view of an alternative embodiment of the multi-article packaging of FIG. 1.

FIG. 9 is a front view of the alternative embodiment of the multi-article packaging of FIG. 8; and,

FIG. 10 is a top view of the alternative embodiment of the multi-article packaging of FIG. 8.
